(57) CLAIM

The ornamental design for a planter, as shown and described.

DESCRIPTION

FIG. 1 is a front perspective view of the planter;
FIG. 2 is a top view of the planter of FIG. 1;
FIG. 3 is a rear perspective view of the planter of FIG. 1;
and,
FIG. 4 is a bottom view of the planter of FIG. 1.
The uneven length broken lines define the bounds of the claimed design and form no part thereof. The even length broken lines depict portions of the planter that form no part of the claimed design.

1 Claim, 4 Drawing Sheets
